(57) **CLAIM**

The ornamental design for a machine display, as shown and described.

DESCRIPTION

FIG. 1 is a perspective view of a machine display showing our new design;

FIG. 2 is a front view thereof;

FIG. 3 is a rear view thereof;

FIG. 4 is a left side view thereof, the right side being a mirror image thereof;

FIG. 5 is top view thereof;

FIG. 6 is a bottom view thereof; and,

FIG. 7 is an enlargement of the encircled area in FIG. 1. The dashed broken lines illustrate structures or features which form no part of the claimed design.

The dot-dash broken lines encircle areas of enlargement.

1 Claim, 6 Drawing Sheets
